WILLIAM C. HIERING, OF NEWARK, NEW JERSEY, ASSIGNOR TO J. E. MERGOTT CO., OF NEWARK, NEW JERSEY, A CORPORATION OF DELAWARE

COLLAPSIBLE BAG FRAME

Application filed October 28, 1929. Serial No. 402,893.

This invention relates to handbags and more particularly to a collapsible frame for handbags.

Heretofore there have been produced handbags provided with frames which enable the bags to be maintained open, such frames being collapsible and forming substantially a rectangle when expanded.

While wide-opening bags of this type have been found advantageous in many respects, the expanding frame is objectionable in that when the frame is extended to form a rectangle, the side portions of the bag are distorted, with the result, that after a few openings the original shape of the bag is destroyed.

It is an object of this invention to provide a collapsible frame which will enable a wide opening of a hand bag, without in any way distorting the body portion of the bag and destroying its shape.

This and other advantages, which will later appear, are accomplished by the simple and practical construction and arrangement of parts hereinafter described and exhibited in the accompanying drawings, forming part hereof, and in which:

Figure 1 represents an elevational view of the bag frame.

Figure 2 represents a plan view showing the frame held in its collapsed condition by means of a clasp.

Figure 3 represents a view similar to Figure 2 showing the clasp disengaged.

Figure 4 represents a plan view of the frame in an extended condition.

Figure 5 represents an end view of the frame.

Figure 6 represents a fragmentary, partly sectional view of the adjacent, hinged and shouldered end portions of end members 15 and 16.

Figure 7 represents a bottom view showing the position of elements when the frame is extended.

Figure 8 represents a similar view showing the position of elements when the frame is collapsed.

Figure 9 represents a sectional view of the frame member.

Figure 10 represents a perspective view showing details of one of the end frame members.

Referring to the drawings, a frame is shown to include parallel longitudinal frame members 11 and 12 and end frame members 13, 14, 15 and 16, the members 13 and 14 being pivotally connected at 17 and the members 15 and 16 being pivotally connected at 18.

End frame members 13 and 15 are pivotally connected to the ends of longitudinal frame member 11 by pins 19 and the end members 14 and 16 are similarly pivotally connected to the member 12. Each of the frame members comprises substantially a sheet metal strip 65 having its upper end bent over to form a channel as shown in Figure 9.

Fixed to the upper portion of member 12 is a metal plate 20, supporting a pivot pin 21 upon which is rotatably mounted a metal clasp 22, the latter having down-extending sides adapted to engage the metal bearing surfaces 23 and 24, on the frame members 11 and 12.

Referring to Figure 5, it will be seen that the end frame members such as 13 and 14 are respectively provided at their upper edges with flattened lips 25 and 26 and at their lower edges with similar lips 27 and 28, the lips being apertured to receive the pivot pin 17. The structure of end members 15 and 16 is identically the same.

The upper edges of members 13 and 14 have the inner walls of the channel cut away to provide shoulders 29 as shown in Figure 10.

In operation, the frame may be collapsed by moving pivots 17 and 18 inwardly towards each other. The frame may be maintained in a collapsed position by moving the clasp 22 to a position such as shown in Figures 1 and 2.

In order to expand the bag, obviously, the pivots 17 and 18 are moved outwardly from each other, but the outward movement of the end members is limited by engagement of the shoulders 29, so that the bag frame is not adapted to assume the shape of a rectangle, but when fully extended has a shape as shown in Figure 4.

The outward movement of the end members may be also limited by engagement of the bent end portions of the adjacent end and side members, as shown, for example, in **5** Figures 7 and 8.

From the above description it will be seen that I have provided a simple collapsible frame for a handbag which frame cannot be extended to such a degree as to distort and **10** destroy the shape of the body of the handbag.

The foregoing disclosure is to be regarded as descriptive and illustrative only, and not as restrictive or limitative of the invention, **15** of which obviously an embodiment may be constructed including many modifications without departing from the general scope herein indicated and denoted in the appended claims.

20 Having thus described my invention, what I claim as new and desire to secure by Letters Patent, is:

25 1. A handbag frame comprising side members and pairs of pivotally connected end members pivoted to said side members, the adjacent ends of said end members being provided with cooperating shoulders to prevent said end members from assuming a position of alignment.

30 2. A handbag frame, comprising side members and pairs of end members pivoted to the side members, the adjacent ends of the end members having flattened lips, one lip resting on the other lip, and one lip being **35** depressed to accommodate the other lip and provide a shoulder to engage the other lip to prevent the end members from assuming a position of alignment.

This specification signed this 25th day of **40** Oct., 1929.

WILLIAM C. HIERING.
